UNITED STATES PATENT OFFICE

WAYNE E. IKERMAN, OF BUTTE, MONTANA, ASSIGNOR OF FORTY PER CENT TO
MEARL L. FAGG, OF BUTTE, MONTANA

AIRPLANE KITE

Application filed September 9, 1929. Serial No. 391,254.

This invention relates to airplane kites, or captive airplanes, an object being to provide a heavier than air device which, when held captive by means of a cable, will be supported 5 in the air without the aid of mechanical power.

Another object of the invention is the provision of an airplane kite which may be used for observation purposes, taking pictures, as 10 well as for advertising and other purposes, the kite being constructed so that it will carry one or more persons with safety.

Another object of the invention is the provision of means for controlling the kite, so 15 that its position may be changed and the kite maneuvered within the radius of its restraining cable.

Another object of the invention is the provision of an airplane kite of novel construction which will eliminate darting and diving 20 movements common to many kites and thus provide a kite which will maintain a steady position and be especially adapted for the above and other purposes.

Another object of the invention is the provision of an airplane kite in which the wings are vertically and horizontally offset and arranged to combine the features of both the 25 bi-plane and monoplane, the positions of the wings being such as to provide a maximum amount of lifting power with a minimum wing spread.

Another object of the invention is the provision of an airplane kite wing of novel construction which will provide increased lifting 30 capacity and a maximum amount of stability.

Another object of the invention is the provision of an airplane kite having an emergency control brake for the landing gear, so 35 that the kite may be more easily controlled in landing.

A further object of the invention is the provision of an airplane kite in which the 40 wings may be folded so that the kite will occupy a minimum amount of space when not in use.

A still further object of the invention is the provision of an amphibian kite having adjustable pontoons so as to increase the useful 45

ness and safety of the kite over land and water.

With the above and other objects in view, the invention further includes the following novel features and details of construction, 50 to be hereinafter more fully described, illustrated in the accompanying drawings and pointed out in the appended claim.

In the drawings:

Figure 1 is a top plan view of an airplane kite constructed in accordance with the invention.

Figure 2 is a side view of the same.

Figure 3 is a front view.

Figure 4 is a plan view of a modified form 55 of the invention.

Figure 5 is a side elevation of the subject matter of Figure 4.

Figure 6 is a plan view of still another form of kite.

Figure 7 is a front view of the kite shown in Figure 6.

Figure 8 is a top plan view of a modified form of tail structure.

Figure 9 is a rear elevation of the same.

Figure 10 is a side elevation of an amphibian kite constructed in accordance with the invention.

Figure 11 is a top view of the same.

Figure 12 is a side elevation of a modified 80 form of kite having relatively large carrying and lifting capacity.

Figure 13 is a plan view of the kite shown in Figure 12.

Figure 14 is a front view of the same.

Figure 15 is a plan view of a further modified form of kite in which the wings are foldably mounted.

Figure 16 is a front view of the kite shown in Figure 15.

Figure 17 is an edge view of one of the wings.

Referring to the drawings in detail where-in like characters of reference denote corresponding parts, the invention as shown 95 comprises a frame 10. This frame includes longitudinally disposed members which are connected by struts 11 and guy wires 12, the construction of the frame being adapted to the particular form of the kite and varies 100

slightly with the different forms of kite illustrated. The general idea of a supporting frame which carries a wing structure and baskets or cars being similar in all of the forms of the invention.

In the form of the invention shown in Figures 1 and 2, the frame 10 has extending laterally therefrom upon opposite sides, wings 13 and 14. These wings are longitudinally spaced and the foremost wings have their leading edges 15 inclined rearwardly, while their leaving edges 16 are disposed at right angles with respect to the frame 10. The wings 13 as well as the wings 14 extend upwardly and outwardly and provide the dihedral type of wing. By providing the inclined leading edge 15 and the right-angled leaving edge 16 for the wings 13, a proper balance and increased stabilizing effect is obtained.

The wings 14 have their leading and leaving edges parallel. The wings 14 however extend beyond the outer ends of the wings 13 and the outer ends of the leading edges of these wings 14 are curved rearwardly as shown at 16 to further increase stability.

The wings 13 are provided with ailerons 17, while the wings 14 are provided with ailerons 18. The ailerons 18 however are positioned beyond the outer ends of the wings 13 so as to be in unobstructed path of air currents or wind forces and provide greater lifting capacity as well as stability in flight.

The leading edges 15 of the wings 13 are curved as indicated at 19 and further act to increase the lifting and stabilizing effect of the kite.

The tail or rear end of the kite is provided with outwardly extending horizontally disposed stabilizer planes 20 and these planes have hingedly secured thereto as indicated at 21, elevator rudders 22, while positioned between these rudders 22 is a rudder 23 which controls the horizontal direction of flight.

The wings 13 and 14 are braced by suitable guy wires 24, 25 and 26, while a reinforcing bar 27 extends longitudinally of the frame and is connected by truss cables 28.

The frame is provided with front and rear cars or compartments 27 and 28 and an intermediate car compartment 29. The car 27 may carry observers or photographers, while the car 29 may accommodate an operator and photographers. For this purpose, the usual control cables may extend into the car 29 and this car may be provided with any ordinary or suitable controlling device.

By constructing the frame in the manner stated and spacing the cars 27, 28 and 29 longitudinally of the frame, both lateral and upward air passages are provided between the cars which further acts to stabilize the kite.

The kite may be provided with a suitable restraining cable 30 which is attached to the

frame by means of a bridle 31. The kite may also be provided with landing gear which includes a carriage 32 and skid 33.

In Figures 4 and 5 of the drawings, the kite as shown includes front wings 34 and rear wings 35 and are also of the dihedral type. The front wings 34 however in this form of the invention have leading and leaving edges parallel, while the rear wings have their leading edges parallel with the edges of the front wings and extend rearwardly to the rear or tail stabilizers 36, the outer edges of the wings 35 being rearwardly and inwardly inclined as shown at 37.

In Figures 6 and 7 the kite has extending from opposite sides of the frame 10, wings 38. The leading edges of these wings are rearwardly inclined as shown at 39 while their side edges are inwardly and rearwardly inclined as shown at 40. The wings 38 may also be of the dihedral type of wing structure.

Instead of having the rear or tail stabilizers extend horizontally outward, these stabilizers may also extend outwardly and upwardly as shown at 41 in Figures 8 and 9 of the drawings. In addition, the outer or side edges of the tail stabilizers 41 may be inclined outwardly and rearwardly as shown at 42.

In Figures 10 to 16 of the drawings, the frames of the kites are substantially the same as the frames of the kites previously described, in that the vertical and horizontal passages are provided.

In Figures 10 and 11 however the kite shown is of the amphibian type so as to provide increased safety for the occupants by providing for landing the kite either on land or water. The kite shown in Figures 10 and 11 therefore is provided with pontoons 43 which are disposed below the cars and may be adjusted with respect thereto.

Also the kite shown in Figures 10 and 11 combines the features of both the monoplane and biplane in that wings 44 and 45 are provided one above the other, while a wing 46 is positioned at the rear of and on a plane intermediate the wings 44 and 45. The wings are thus both vertically and horizontally spaced so that the rear wing 46 will receive air from the trailing edges of the forward wings 44 and 45, the latter being spaced an appreciable distance.

The wings 44, 45 and 46 may be constructed as shown in Figure 17 of the drawings. This wing has a lower cambered or slightly curved leading portion at *a* and is upwardly curved rearwardly from *a* to *b* so as to provide a maximum amount of lifting force, this curved portion terminating at *c*.

From this point, to the point indicated at *d*, the wing curves downwardly so as to guide or direct the air stream downwardly and rearwardly and along the upwardly curved portion extending from *d* to *e*, the latter being the trailing or leaving edge of the wing. The

leading edge of the wing which is indicated at *f* is upwardly curved at *g*, the camber extending from this point to the point *i* with its highest point at *h*. This causes the air to travel close or hug the wing at the top or upper edge from *g* to *h*. The upper surface of the wing curves downwardly from *i* to *k* with its low point approximately at *j*, so that the air travels along this curved portion and straight outward along the upper horizontal portion between the points *a* and *l*. This in addition to the lifting power provided directs the air from the forward wings to the rear wings so that the latter will have increased lifting capacity. The upper horizontal trailing edge of the wing acts as a counterbalance and will prevent the nose of the kite from tilting downward should the wind suddenly stop blowing.

Also by reference to Figures 10 and 11 of the drawings it will be seen that the leading edge of the upper wing 44 is an appreciable distance in advance of the leading edge of the lower wing 45.

In Figures 12, 13 and 14, the wing arrangement is similar to that shown in Figures 10 and 11, except that the upper and lower wings 47 and 48 are arranged between the rear wing 49 and a forward wing 50. The wings 49 and 50 are arranged substantially in the same horizontal plane and on a plane between the wings 47 and 48, the former wings being arranged after the manner of a monoplane, while the wings 47 and 48 are arranged similar to the wings of a biplane. The forms of the invention shown in Figures 10 to 14 thus provide a combination bi-plane and monoplane.

The kite shown in Figures 12, 13 and 14 is provided with main landing wheels 51 and with a forward or nose landing wheel 52 and a rearward or tail landing wheel 53. In addition, the wheels 50 are provided with suitable brakes 54 which are connected with the rock shaft 55. This shaft extends transversely of the landing gear and operates in bearings 56. The shaft 55 is connected with the brakes 54 as indicated at 57, while suitable connection is made from the rock shaft 55 to a foot pedal arranged within convenient reach of the occupants of the kite.

An engine 58, preferably of the motorcycle type, is mounted upon the lower wing 48 upon each side of the kite. These engines operate propellers 59.

Ailerons may be provided upon one or more of the wings. For example, the wings 44 shown in Figures 10 and 11 of the drawings may be provided with ailerons 60, while the wings 47 and 50 shown in Figures 12 and 13 of the drawings may be provided with ailerons 61 and 62 respectively.

The kite shown in Figures 15 and 16 is provided with spaced upper and lower wings 63 and 64, while rearwardly of these wings

is a wing 65. All of these wings are hinged-ly secured to the frame of the kite as shown at 66 so that the wings may be folded when the kite is not in use. In addition, the rear stabilizers 67 of the kite are also hinged to the frame as shown at 68 so that these stabilizers may be likewise folded.

While the kites described are primarily intended to be used as captive kites, they are provided with engines and traction propellers as shown and described. These engines and propellers however are primarily intended for use in an emergency, such as when the restraining cable breaks, or where it is necessary to make a landing at some remote point from the point at which the kite is being flown. This will be especially useful in war time observation if danger should suddenly arise as the occupants or operator could cut the restraining cable and fly to a safe landing.

The invention is susceptible of various changes in its form, proportions and minor details of construction and the right is herein reserved to make such changes as properly fall within the scope of the appended claim.

Having described the invention what is claimed is:

A kite comprising an elongated frame including a plurality of connected longitudinally disposed members, struts and guy wires connecting the members, longitudinal reinforcing members disposed above and connected to the frame, steering and elevating means at the rear end of the frame, front and rear pairs of wings secured to the frame and inclining upwardly and outwardly therefrom, the leading edge of the front pair of wings disposed on an incline extending outwardly and rearwardly of the frame and the leaving edge of the front wings arranged at right angles to the frame, said rear wings having the leading and leaving edges disposed parallel and at right angles to the frame, and landing means at the front and rear ends of the frame.

In testimony whereof I affix my signature.
WAYNE E. IKERMAN.
